UNITED STATES PATENT OFFICE.

MORRIS P. BRAY, OF ANSONIA, CONNECTICUT, ASSIGNOR TO DAVID H. FANNING, OF WORCESTER, MASSACHUSETTS.

CORSET-WAIST.

SPECIFICATION forming part of Letters Patent No. 432,787, dated July 22, 1890.

Application filed December 20, 1889. Serial No. 334,454. (No model.)

To all whom it may concern:

Be it known that I, MORRIS P. BRAY, of Ansonia, in the county of New Haven and State of Connecticut, have invented a new Improvement in Waists; and I do hereby declare the following, when taken in connection with accompanying drawings and the letters of reference marked thereon, to be a full, clear, and exact description of the same, and which said drawings constitute part of this specification, and represent, in—

Figure 1, a side view of the waist complete; Fig. 2, an inside view of one-half the waist; Fig. 3, a transverse section through one-half the waist.

This invention relates to an improvement in the construction of waists for ladies, misses, and children, in contradistinction to corsets, the object of the invention being to construct the waist so as to present the usual exterior shape and appearance, but upon its interior to present a material of a woolly or absorbent character, and such as may be readily charged with any desired medicating or deodorizing material; and the invention consists in the construction as more fully hereinafter described, and particularly recited in the claim.

A represents the outer thickness of the waist, which is cut in parts from cotton, linen, silk, or like woven material in substantially the usual manner of cutting the exterior of such waists.

B represents the interior thickness, which is made from wool—either woven wool or felt, felt being preferred. This inner thickness extends over the inner surface of the outer thickness nearly to the edges of each half the waist, as seen in Figs. 2 and 3. The outer thickness is turned over onto the inside, and so as to lap onto the wool inside at both edges, as seen in Fig. 3, the one edge forming the eyelet-strip for the back and the other the fastening-edge for the front.

Vertical cords, as d d, are introduced between the two thicknesses, and stitches run each side, as indicated in Fig. 1, to inclose the said cords and secure them in place.

The inner thickness may be molded to

shape in felt, or it may be made in parts cut to shape and the parts stitched together. 50 From the rear side of each part a shoulder-strap C extends over to a securing device on the front.

By making the inner thickness of wool it makes that surface a ready absorbent, so that 55 in the manufacture of the waist it may be charged with any suitable medicating or deodorizing material.

The exterior thickness, being woven from cotton, linen, or similar material, is inelastic, 60 so that it serves to maintain the shape of the waist without undue strain upon the wool portion, which could not otherwise retain the required shape. The entire strain of the waist comes upon the outer thickness, so that no 65 substantial tension is brought upon the inner thickness, but it is left free in its natural or normal condition. The cords aid in imparting shape to the waist.

The inner thickness is charged with a medicating or deodorizing material before the waist is made up, and this may be applied in the form of steam, vapor, or with an atomizer, the wool readily absorbing the material under such circumstances, and will retain it for 75 a great length of time.

I do not wish to be understood as claiming, broadly, a waist or corset having a wool lining, as such, I am aware, is not new.

I claim—

The herein-described waist, consisting of an outer thickness of woven non-elastic fabric combined with an inner thickness of wool, the outer thickness turned upon the inside and so as to lap upon the inner surface of the 85 said wool at both edges, and so as to form the eyelet and fastening-strips substantially independent of said wool thickness, with cords introduced between said thicknesses in pockets formed by lines of stitches corresponding 90 to the position required for said cords, substantially as described.

MORRIS P. BRAY.
